UNITED STATES PATENT OFFICE.

OLIVER G. WOOD, OF PHILADELPHIA, PENNSYLVANIA.

PHOTOGRAPH OR LIKE MOUNT.

Application filed January 10, 1924. Serial No. 685,338.

To all whom it may concern:

Be it known that I, OLIVER G. Wood, a citizen of the United States, residing at Philadelphia, in the county of Philadelphia, 5 State of Pennsylvania, have invented a certain new and useful Photograph or like Mount, of which the following is a specification.

This invention, generally stated, relates to 10 photographic and like mounts such as are usually made of heavy paper for the display of portraits and other pictures. The leading object of the present invention is to provide a mount of this character so arranged, connected and constructed that there 15 is visible at all times upon the display face of the backing certain indicia as, for instance, the name of the photographer. Other and further objects not at this time appearing 20 will be hereinafter more particularly referred to.

The invention consists of the novel construction hereinafter described and finally claimed.

25 The nature, characteristic features and scope of the invention will be more fully understood from the following description taken in connection with the accompanying drawings forming part hereof, and in which: 30 Fig. 1, is a view in elevation of a mount in open position to expose the backing display face.

Fig. 2, is a view in elevation showing a slightly modified form.

35 Fig. 3, is a view corresponding to Fig. 1 with the flaps in folded position, and

Fig. 4, is a view corresponding to Fig. 2 with the flaps in folded position.

40 For the purpose of illustrating my invention I have shown in the accompanying drawings two forms thereof which are at present preferred by me, since the same have been found in practice to give satisfactory and reliable results, although it is to be 45 understood that the various instrumentalities of which my invention consists can be variously arranged and organized and that my invention is not limited to the precise arrangement and organization of the instrumentalities as herein shown and described.

50 Referring to the drawings in detail, the numeral 1 designates a backing provided with laterally disposed foldable flaps 2 and 3. The backing has a display face which, as shown in Fig. 1, may be provided with corner clips 4 for the insertion of a photograph

or other picture, or it may be a plain surface as indicated at 5 in Fig. 2. The flaps 2 and 3 are adapted to be folded over upon the display face of the backing, as clearly 60 shown in Figs. 3 and 4. The backing and the flaps are so constructed and proportioned with respect to one another that in the overlapping position thereof at least a portion of said backing display face remains 65 uncovered to disclose indicia thereon. In Fig. 1 this exposed portion is indicated by the numerals 6 and 7, and in Fig. 2 by the numeral 8. In other words, in Fig. 1 the spaces 6 and 7 are at the top and bottom respectively of the mount and in Fig. 2 the space 8 is at the bottom only of the mount. The purpose of providing these spaces is to provide a display space for certain indicia, for instance, the name of the photographer. 70 Thus when the flaps 2 and 3 are folded over in interlapping position, while the photograph, picture or the like is entirely hidden the space with the indicia thereon is clearly 75 visible, as is clearly seen in Figs. 3 and 4. 80 By reason of this construction the photographer, for instance, derives constant advertisement whether the photograph is hidden by the flap or is in plain view by reason of the flaps being open. In Fig. 1 the flaps 85 2 and 3 are cut-away at the top and at the bottom as at 9 and 10 respectively so that when in folded position the parts 6 of the backing projects above the flaps and the space 7 of the backing depends below the 90 flaps 2 and 3. One flap, that designated 2 in the drawings, is provided with a plurality of slits or slots 11 and 12, the other of said flaps, that designated 3 in the drawings, is provided with a tab 13. When the flaps 95 are folded in the position shown in Figs. 3 and 4 the tab 13 is inserted through slit 11 for securely interlocking the parts together. When the flaps 2 and 3 are folded in the rear 100 of the backing tab 13 is inserted through slit 12 in order to interlock the flaps for supporting the backing as an easel, as shown and described in my co-pending application for Letters Patent, Serial No. 621,538, filed Feb. 27, 1923.

105 It will now be apparent that I have devised a novel and useful construction which embodies the features of advantage enumerated as desirable in the statement of the invention and the above description and while 110 I have in the present instance shown and described the preferred embodiment thereof

which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:

A phonograph or like mount comprising a backing provided with lateral, foldable flaps adapted to be folded into overlapping position upon the display face of said backing, which display face is arranged to receive a photograph and also to have depicted

thereon the name of the photographer making such photograph, the backing and flaps being so constructed and proportioned with respect to one another that in said overlapping relation of said parts at least a portion of said backing display face remains uncovered to disclose the name of the photographer making said photograph, and means for interlocking said flaps with respect to one another.

In testimony whereof, I have hereunto signed my name.

OLIVER G. WOOD.
